UNITED STATES PATENT OFFICE.

HARRY A. INMAN, OF AMSTERDAM, AND CHARLES T. BLOOMER, OF NEWARK, NEW YORK, ASSIGNEES OF ONE-THIRD TO SAID INMAN, ONE-THIRD TO BLOOMER BROS. COMPANY, OF NEWARK, NEW YORK, AND ONE-THIRD TO EMPIRE PAPER TUBE & BOX CO., OF NEW YORK, N. Y.

RECEPTACLE.

1,172,997.

Specification of Letters Patent.

Patented Feb. 22, 1916.

Application filed June 26, 1915. Serial No. 36,475.

To all whom it may concern:

Be it known that we, HARRY A. INMAN and CHARLES T. BLOOMER, citizens of the United States, residing, respectively, at Amsterdam and Newark, in the counties of Montgomery and Wayne and State of New York, have invented a new and useful Receptacle, of which the following is a specification.

10 The present invention appertains to receptacles, and aims to provide a novel and improved receptacle which may be used generally for holding liquid as well as solid or semi-liquid contents, and which is of neat and attractive appearance and construction so as to render the same practical for most all purposes.

15 The present receptacle has its body or side walls composed of paper, cardboard or equivalent stock, having a bottom or end of sheet metal secured to one end thereof, and a sheet metal ring secured to the other end thereof and adapted for the reception of a cap or closure, the bottom and ring being applied to the body in a unique manner, whereby the receptacle will be thoroughly substantial or firm in construction, and will serve its office in a thoroughly efficient and advantageous manner.

20 Another feature of the invention resides in the fact that a plurality of the receptacles may be nested together, whereby they may be boxed and shipped within small encompass, for purpose of economy, the receptacles when nested not being liable to injure one another.

25 The invention also resides in improved details of construction, to enhance the utility of the device, and to enable the same to be manufactured cheaply and in a practical manner.

30 With the foregoing and other objects in view which will appear as the description proceeds, the invention resides in the combination and arrangement of parts and in the details of construction hereinafter described and claimed, it being understood that changes in the precise embodiment of the invention herein disclosed can be made 35 within the scope of what is claimed without departing from the spirit of the invention.

The invention is illustrated in the accompanying drawing, wherein:—

Figure 1 illustrates a plurality of the receptacles in nested relation, one of the receptacles being shown in section, and the others being shown in elevation. Fig. 2 is a top view of one receptacle. Fig. 3 is a cross section thereof taken on the line 3—3 of Fig. 1. Fig. 4 is a bottom view of the receptacle. Fig. 5 is an enlarged vertical section of the receptacle taken on the line 5—5 of Fig. 2, portions being broken away, and a cap or closure disk being illustrated in position for closing the receptacle. Fig. 6 is an enlarged sectional detail illustrating the manner in which the bottom is attached to the body.

In turning out the invention, the body 1 of the receptacle is formed from a blank of paper, cardboard, or equivalent stock, which has the overlapped portions 2 that are pasted or otherwise secured together. The body 1 is of frusto-conical or tapered form, which is not only desirable in the use of the receptacle, but which also enables a plurality of the receptacles to be nested compactly together for purpose of convenient and inexpensive shipment.

The bottom 3 is constructed of sheet metal or equivalent material and is of circular or disk-like form, the bottom 3 fitting within the smaller end portion of the body 1 at a point spaced above the lower or smaller end of the body. This bottom 3 is provided with a downturned marginal flange 4 fitting snugly within the lower end portion of the body, and the edge portion of the flange 4 is bent outwardly and upwardly around the lower end of the body 1, as at 5, to embrace the outturned lower end 6 of the body. The edge 7 of the flange 4 grips the stock and clamps it securely against the body of the flange 4, and holds the lower end 6 of the body within the bent or curled portion 5. The portion 5 provides an outstanding annular bead carried by the lower end of the body, which not only reinforces or strengthens the body, but which also adds to the appearance thereof and serves as an effective means for supporting the receptacle upon a surface.

Fitting snugly within the upper or larger end portion of the body 1, is a sheet metal ring 8 whose lower edge has an inturned annular flange or lip 9, which is relatively

narrow. The upper edge portion of the ring 8 is bent or curved outwardly and downwardly, as at 10, to embrace the outturned upper end 12 of the body, and the upper edge 13 of the ring 8 grips the stock and clamps it tightly against the body of the ring 8. The curled or bent portion 10 provides an outstanding annular bead carried by the upper end of the body, which matches 5 the lower bead. The two beads protect the body, since when the receptacle is laid or handled upon a surface, the beads will contact therewith, and will hold the body spaced from said surface so that the body will not 10 be dented or otherwise injured during the handling of the receptacle.

The ring 8 and its flange 9 provide a seat for the reception of the cap or closure disk 14 constructed of cardboard or equivalent 20 material, whereby the cap 14 will close the receptacle or vessel. It is preferable to provide the ring 8 with an inwardly projecting annular rib 15 overhanging the flange 9 and under which the margin of the cap 14 is engageable to hold the cap tightly upon the flange 9, for preventing the cap from being accidentally detached, and also to prevent leakage.

The sheet metal bottom and ring being 30 secured to the ends of the body will reinforce and strengthen the body, whereby the receptacle will not become bent or distorted out of shape readily. The receptacle may be inexpensively manufactured, since the 35 greater or body portion of the receptacle is constructed of paper, cardboard, or other inexpensive material, which, moreover, renders the receptacle sanitary and hygienic in use. The receptacle may be employed for 40 divers purposes for containing and handling various liquids and solids, and it is of course understood that the receptacle may be constructed in various sizes and proportions to vary the capacity thereof.

45 When the receptacles are being shipped in quantity, they may be compactly nested together, not only for purpose of economy, but also for purpose of protecting the receptacles during transit, so that they are not liable to 50 be broken or injured. A series of the receptacles may be conveniently nested together; as suggested in Fig. 1. Considering two of the receptacles in nested relation, the lower bead of the inner receptacle will bear 55 against the body of the outer receptacle,

while the flange 9 of the outer receptacle will bear against the body of the inner receptacle, so that the receptacles are prevented from vibrating or jostling, and in this manner, the receptacles are held firmly 60 at their opposite ends to prevent injury thereto.

In practice, the present vessel or receptacle is a most desirable and convenient one, and has numerous advantages which will be apparent to those familiar in the art without further comment being necessary.

An important feature of the invention resides in the fact that the bottom 3 may be struck or cut out of the same sheet metal 70 blank, as the ring 8, whereby the bottom 3 being cut from the blank leaves the ring 8. This provides for a saving of material, since there is no waste, it being noted, that the bottom being of smaller diameter than the 75 upper ring 8 enables the bottom and ring to be readily cut from one blank as indicated. It is also preferable to construct the body 1 of the receptacle out of moisture-proof paper or material.

Having thus described the invention, what is claimed as new is:

A receptacle adapted to be nested with others of like construction, comprising a frusto-conical tapered paper body, a sheet 85 metal bottom fitting within the smaller end of the body and having an outstanding bead embracing said end, and a sheet metal ring fitting snugly within the larger end of the body and having an inturned flange at its 90 lower edge and an outstanding bead at its upper edge embracing the larger end of the body, the first mentioned bead and inturned flange being of such proportions that when a number of the receptacles are nested, the 95 beads and inturned flanges of the several receptacles will contact simultaneously with the respective bodies.

In testimony that we claim the foregoing as our own, we have hereto affixed our signatures in the presence of two witnesses.
